STAMP AND LABEL BOX

Jacob Yacker and Walter S. Kirsch, Brooklyn, N. Y.

Application March 28, 1936, Serial No. 71,394

2 Claims. (Cl. 217—7)

This invention is a stamp and label box adapted to be used by shipping clerks and mailing clerks in business establishments, offices, etc., as a convenient depository for stamps and labels, whereby stamps of various denominations and labels of various kind may be efficiently segregated for convenient access.

Shipping and mailing clerks use at various times stamps of several denominations and it is almost the universal practice to keep these stamps in separate envelopes with the denominations marked on the outside, so that, when any particular stamp is desired, the envelope is opened and one or more stamps removed. It is not uncommon in the mailing of parcels and the like to handle three or four different envelopes in order to get stamps of the proper denomination to fulfill the postal requirements.

The label problem constitutes another source of annoyance. These labels are generally contained in separate receptacles or boxes which lie at random on the desk of the shipping clerk and have to be sorted over every time a particular type of label is required.

The foregoing common practice constitutes an annoyance and waste of time. It slows down mailing and shipping facilities of an organization and is altogether undesirable, yet, up to the present time, no satisfactory solution has been found.

The present invention provides a simple and efficient solution of the problem through the provision of a box provided therein with compartments adapted to contain stamps of different denominations and labels of different kinds in a convenient and accessible manner. One or more of the compartment walls of the box are hinged and are provided with appropriate catch devices, so that two or more compartments may be merged into one in the event that a larger single compartment is desired in the place of two or more smaller compartments. Furthermore, the box provides convenient means for handling of labels in strip form, such, for example, as air mail labels which are commonly employed in shipping and mailing departments.

Features of the invention, other than those adverted to, will be apparent from the hereinafter detailed description and claims, when read in conjunction with the accompanying drawing.

The accompanying drawing illustrates one practical embodiment of the invention, but the construction therein shown is to be understood as illustrative, only, and not as defining the limits of the invention.

Figure 1 is a perspective view showing a box embodying the present invention.

Figure 2 is a fragmental plan view of the interior box compartments showing the manner in which certain compartment walls may be hinged 5 to merge two or more compartments.

Figure 3 is a section on the line 3—3 of Figure 1; and

Figure 4 is a perspective view showing a strip label dispensing device which is associated with 10 one of the compartments.

Referring to the drawing, 1 designates a body of a box which, in practice, may be of any appropriate shape and size, but is preferably relatively shallow, so that it may be conveniently positioned 15 within the drawer of a desk or table or placed for safe keeping in a safe or locked box.

The box body 1 may be provided with a cover of any appropriate kind. In the more expensive types of box, made in accordance with this invention, we prefer to employ a rolled top, similar to that commonly used on rolled top desks, but inasmuch as this type of closure is well known, we have not considered it necessary to illustrate the same in the drawing. For the purpose of 25 illustration, we have shown the closure in the form of a hinged cover 2 which may be locked in closed position, when desired, by an appropriate lock constituting the parts 3 and 4, one of which is mounted on the cover and the other on 30 the box body. When a hinged cover of the character described is employed, the inner face of the cover forms a convenient space on which is printed postal information appropriate to letter mail, air mail and parcel post and generally showing rates, zones, and other information useful to 35 the user of the box.

The interior of the box body is divided by longitudinal and transverse walls into a series of compartments. We preferably provide along 40 the front portion of the box body a row of compartments designated generally by the reference characters 5, 6, 7, and 8. These compartments may all be of the same or different sizes and are adapted primarily to contain labels, stickers, etc., such as have printed thereon, for example, "Letter Mail", "Special Delivery", "Air Mail" or "Parcel Post". The labels fit into these compartments set on edge, so that they are readily accessible for convenient withdrawal. 45

In the corner compartment 8 we house a strip label dispensing device, a convenient form of which is shown best in Figures 3 and 4. It may be economically made of sheet metal by bending an elongated strip of sheet metal into rec- 55

tangular form to produce a bottom wall 9, end walls 10 and 11 and a top wall 12. The ends of the strip may be united by providing the bottom wall 9 with an upstanding flange 13 having slits 5 and by providing the lower end of the end wall 11 with tongues adapted to be passed through said slits and bent over, as shown best in Figure 4 as at 14.

Labels in folded strip form are adapted to 10 be contained within this structure and passed through a slot 15 in one end of the top wall 12 and thence carried along the exterior surface of said wall in the direction of the arrow in Figure 4 beneath a retaining member 16.

15 This retaining member may also be stamped from sheet metal and of inverted U-shape form to provide opposite side flanges 17 having at their lower ends tongues similar to the tongues 14 adapted to be passed through slots in the top 20 wall 12 and bent over to hold the retainer 16 in place. The end edge 18 of the retainer is a cutting edge, so that the strip label, after extending beneath the retainer and beyond the edge 18, may be withdrawn to the desired extent and torn off against said edge. To facilitate the longitudinal movement of the strip label, the upper portion of the retainer is cut away to provide an operating slot 19 which is 25 preferably sufficiently large, so as to permit the label, when in place on the dispenser, to be read and properly identified by the user without necessitating the withdrawal of the label. The device shown in Figure 4 is, as stated, adapted to be received in the compartment 8, so as to 30 fit said compartment snugly and this makes it unnecessary to provide side walls for the strip label container.

In addition to the compartments 5-8, inclusive, the box is shown as having additional compartments 20-25, inclusive. The compartments 40 20 and 21 are separated by a transverse wall 26 which is shown as hinged to a longitudinal wall 27 by a hinge 28. This hinge is a spring hinge and is provided therein with a spring 29, which 45 serves to normally hold the wall 26 in a position to separate the compartments 20 and 21. However, said wall 26 may, if desired, be moved, as indicated by the arrow in Figure 2, to merge the compartments 20 and 21 and is provided at its 50 free end with a spring catch 30 which, when the wall 26 is moved into the dotted line position of Figures 1 and 2, will pass through a slot 31 in the wall 27 and thus lock the wall 26 in retracted position, so that, in lieu of the two smaller compartments 20 and 21, a large or double compartment is provided. When the catch 30 is released, the spring 29 will return the wall 55 26 to the full line position of Figures 1 and 2 and the small projection 32 may be received into a depression in the wall 33 to serve to hold the wall 26 against inadvertent shifting. Additional walls of the box may be made pivotal as described in connection with the wall 26 and we have shown one additional wall 34 pivoted 60 to the wall 27 in the same way.

In a box made as described labels are conveniently disposed in the compartments 5-8, while the stamps in loose, strip, sheet or roll form are deposited in the other compartments in accordance with predetermined denominational designations, the partitions being shiftable as stated to provide sufficient space for particular denominations. In each case, however, the stamps are kept in an accessible way where their type and character can be easily observed 10 and from which they may be removed without inconvenience or delay.

It will of course be understood that the box of this invention may be made of any suitable material and of any appropriate size and with 15 any desired number of compartments depending upon conditions.

The foregoing detailed description sets forth the invention in its preferred practical form, but the invention is to be understood as fully 20 commensurate with the appended claims.

Having thus fully described the invention, what we claim as new and desire to secure by Letters Patent is:

1. A stamp and label box comprising a box 25 body provided therein with a fixed partition wall dividing the interior of the box body into a plurality of compartments and having therein a slot, at least one hinged wall having at one of its ends a spring hinge mounted on the fixed 30 partition wall and serving to normally maintain the hinged wall in a position to subdivide one of the compartments in the box body into two smaller compartments, but being retractable against the tension of the spring hinge to 35 merge said smaller compartments, and a spring label clasp on the hinged wall adapted to enter into the slot of the fixed partition to hold the hinged wall in retracted position when the clasp is engaged with the slot.

2. A stamp and label box comprising a box 40 body provided therein with a fixed partition wall dividing the interior of the box body into a plurality of compartments and having therein a slot, at least one hinged wall having at one of its ends a spring hinge mounted on the fixed partition wall and serving to normally maintain the hinged wall in a position to subdivide one of the compartments in the box body into two smaller compartments, but being retractable against the tension of the spring hinge to merge said smaller 45 compartments, and a spring clasp on the hinged wall adapted to enter into the slot of the fixed partition to hold the hinged wall in retracted position when the clasp is engaged with the slot, there being a depression in a fixed wall 50 of the box adjacent the free end of the hinged wall when the latter is in subdividing position, and a projection on the spring clasp adapted to engage with both said depression and said slot when the hinged wall is in its respective positions to preclude inadvertent movement of said 55 hinged wall.
